UNITED STATES PATENT OFFICE.

ABRAHAM P. RINDSKOPF AND HENRY P. RINDSKOPF, OF BROOKLYN,
NEW YORK.

DESIGN FOR A DRESS-SHIELD.

SPECIFICATION forming part of Design No. 21,662, dated June 28, 1892.

Application filed January 7, 1892. Serial No. 417,319. Term of patent 7 years.

To all whom it may concern:

Be it known that we, ABRAHAM P. RINDSKOPF and HENRY P. RINDSKOPF, citizens of the United States, and residents of Brooklyn, in the county of Kings and State of New York, have invented and produced a new and original Design for Dress-Shields, of which the following is a specification.

Reference is to be had to the accompanying drawing, forming a part of this specification, in which the figure is a front view of our newly-designed dress-shield.

A represents the body member of the dress-shield, and B the sleeve member. These are correspondingly curved at their upper edges, as indicated at a. The said sleeve member B

is of short depth as compared to the depth of the body member A, and its lower edge is curved, as shown at b. The body member A terminates at a point c at about the center line of the shield and below the sleeve member B, and its outer edges are curved, as shown at d, from the point c to the upper points e of the shield.

What we claim is—

The design for dress-shields herein shown and described.

ABRAHAM P. RINDSKOPF.
HENRY P. RINDSKOPF.
